UNITED STATES PATENT OFFICE.

DONALD BARNS MORISON, OF HARTLEPOOL, ENGLAND.

PISTON-RING.

SPECIFICATION forming part of Letters Patent No. 757,214, dated April 12, 1904.

Application filed February 7, 1903. Serial No. 142,394. (No model.)

To all whom it may concern:

Be it known that I, DONALD BARNS MORISON, a subject of the King of Great Britain and Ireland, and a resident of Hartlepool, in the county of Durham, England, have invented certain new and useful Improvements in and Connected with Piston-Rings, of which the following is a specification.

It is found in practice, particularly with steam or gas of very high pressures, that the pressure acting on the inner circumference of piston-rings causes excessive friction between the outer circumference of the piston-ring and the cylinder-walls and a consequent wear-
ing away of the material of the cylinder or the ring, or both. It is also found that if a piston-ring fits a cylinder accurately very little lateral pressure is necessary in order to obtain the desired steam-tightness.

My invention relates to a device for limiting the expansion of piston-rings to a certain predetermined amount; and it consists of a preferably flat ring which is received within a recess in the piston ring or rings or partly in a recess in the ring and partly in the junk-ring or cover of the piston in such a manner that the limit-ring encircles the lip or shoulder formed by the recess in the piston-ring.

When the piston-ring is first placed within the cylinder, the exterior diameter of the limit-ring may be equal or slightly less than the diameter of the piston; but the inner diameter of the limit-ring is preferably slightly greater than the outer diameter of the lip or shoulder on the piston-ring, so that when the pressure acting on the inner surface of the piston-ring causes the outer surface of the ring to wear this wear continues only up to that point when the external diameter of the shoulder on the piston-ring is equal to the interior diameter of the limit-ring, and as the limit-ring causes the piston-ring to wear uniformly on its outer surface and tends also to maintain the cylindricity of the piston-ring it is found that the accuracy with which the piston-ring fits the cylinder when the limit of wear has been reached is such that not only is the leakage of steam minimized, but the friction between the ring and the cylinder-
wall is also minimized, thereby increasing the

mechanical efficiency of the engine. When a further expansion of the piston-ring is desired, the limit-ring is removed and its inner diameter increased by filing or otherwise. In order to facilitate increasing the diameter, the inner surface of the limit-ring is reduced—as, for example, by means of a groove—so that the surface to be filed is lessened. This reduction of the surface is an important feature, as it reduces the time necessary to make the adjustment. It is evident that the adjustment may also be obtained by decreasing the diameter of the shoulder forming the recess in the piston-ring.

Another feature of practical value in my invention is that facilities are afforded for obtaining exactly the adjustment required, as if the piston-ring is placed within the cylinder and the amount of the opening at the division of the ring noted the piston-ring may then be removed from the cylinder and the inner diameter of the limit-ring so adjusted that when the limit-ring is placed in the recess of the piston-ring the amount of opening at the division of the piston-ring can be accurately measured and the limit of expansion determined.

My invention is applicable to various forms and types of piston-rings, and is also particularly suitable for the rings of piston-valves.

In the accompanying sheet of drawings, Figure 1 shows, partly in section, a piston-ring and a limit-ring constructed in accordance with and embodying my invention. Fig. 2 represents the said piston-ring and limit-ring as inserted into a piston. The piston-ring, limit-ring, and part of the piston are shown in section. Fig. 3 is a similar sectional view showing the piston illustrated in Fig. 2 placed within a cylinder, for sake of simplicity only a part of the cylinder-wall being shown in section. Fig. 4 is a sectional view of a piston provided with three piston-rings and three limit-rings, the piston-rings being separated by suitable distance-rings. Fig. 5 is a sectional view of a piston placed within a cylinder, the piston-ring being provided with two limit-rings; and Fig. 6 is a similar view to Fig. 5. In this modification, however, the limit-rings are placed partly within a recess of the

piston-ring and partly within a recess of the piston-body or piston-cover, respectively.

Similar letters of reference refer to similar parts throughout the several figures.

5 The piston-ring *a*, Fig. 1, is provided with a limit-ring *b*, which is placed within a recess *a'* of the piston-ring. The limit-ring encircling the projecting lip or shoulder *a''* of the piston-ring limits the expansion of the piston-ring to a predetermined amount.

The arrangement of piston-rings within pistons is well known and may be effected in various ways. If, for example, a piston consisting of a body *k*, Fig. 2, a cover *d*, and a piston-ring *a*, provided according to this invention with a limit-ring *b*, is placed within a cylinder *w*, Fig. 3, the cylinder-wall compresses the piston-ring in the manner shown in Fig. 3. In this position the exterior diameter of 10 the shoulder *a''* is smaller than the interior diameter of the limit-ring *b*. The wear of the outer circumference of the piston-ring gradually reduces this difference until the lip or shoulder *a''* of the expanding piston-ring bears 15 upon the interior rim or edge of the limit-ring. When the piston-ring has expanded into this position, the piston-ring held or secured against further expansion by its limit-ring fits the cylinder accurately. This is of great 20 practical importance, as a piston working as 25 it generally does in high-pressure steam or gas is very liable to be adversely affected by the consequent friction, the desired steam or gas tightness being obtained at the same time 30 by the said accurate or snug fitting of the piston-ring.

The modification illustrated in Fig. 4 shows a plurality of piston-rings *a*, separated by distance-rings *c* and provided with limit-rings *b*. 40 Fig. 5 shows likewise a section of a piston, provided between its body *k* and junk-ring or cover *d* with a piston-ring *f*, acted upon by suitable springs *e* and encircled by two limit-rings *b*. The limit-ring may also be placed 45 partly within a recess of the piston-ring and partly in a recess of the piston, as will be seen in Fig. 6, in which the limit-rings *b* are each in a recess formed partly in the piston-ring and partly in the body *k* or cover *d*, respectively. 50 In this example the piston-ring consists of two parts *g*, which are separated by springs *h*.

In order to facilitate increasing the diameter, the inner surface of the limit-ring is reduced by means of a groove *b'*, so that the surface 5 to be filed is lessened.

Having fully described my invention, what I claim, and desire to secure by Letters Patent, is—

1. The combination with a piston and its 6 cover, of a packing-ring between, free to expand, and a continuous ring independent of the cover to limit the expansion of the packing-ring, substantially as set forth.

2. A packing for pistons comprising a split 6 ring having a shoulder at its inner periphery and a continuous ring encircling the shoulder to limit the expansion of the split ring.

3. A packing for pistons comprising a split 7 ring having shoulders formed on its opposite flat faces and continuous rings encircling the shoulders to limit the expansion of the split rings, substantially as and for the purposes set forth.

4. The combination with a piston and its 7 cover, of a piston-packing between them and an independent continuous ring of less diameter than the bore of the cylinder into which the piston fits to surround a portion of the packing and limit its expansion, substantially 8 as set forth.

5. The combination with a piston and its 8 cover, of a packing-ring having a lateral shoulder and a continuous ring having a thickness about equal to the height of the shoulder, and 9 surrounding it; and a groove cut in the inner circular face of the said continuous ring, substantially as and for the purposes set forth.

6. The combination with a piston having a body, a cover and a peripheral groove, one 9 wall of which is formed by the cover and the opposite wall in the body, oppositely-situated circular grooves in the opposite walls of the peripheral groove in the piston, an expansible packing in the groove in said piston having 9 grooves on its opposite faces and a continuous ring lying partly in a groove in the packing and partly in a groove in a side wall of the peripheral groove of the piston, substantially as described.

DONALD BARNES MORISON.
